METHOD OF AND MEANS FOR LOCATING A LIGHT AT FOCAL POINT OF LENSES

Filed Jan. 25, 1926

UNITED STATES PATENT OFFICE.

DANIEL J. McCARTHY, OF ELGIN, ILLINOIS, ASSIGNOR TO CHICAGO RAILWAY SIGNAL & SUPPLY COMPANY, OF CARPENTERSVILLE, ILLINOIS, A CORPORATION OF ILLINOIS.

METHOD OF AND MEANS FOR LOCATING A LIGHT AT FOCAL POINT OF LENSES.

Application filed January 25, 1926. Serial No. 83,431.

The invention relates to a method of and means for locating a light at the focal point of lenses.

One of the objects of the invention is the provision of an improved method of quickly locating a lamp at the focal point of a lens or combination of lenses and for visually determining, with accuracy, when the lamp occupies the desired position, and means 10 for carrying this new mode of procedure into effect.

Other objects, advantages and benefits of the invention will become apparent to persons skilled in the art from a consideration 15 of the following description and the drawings forming a part of this specification wherein:

Figure 1 is a vertical central section of a lens-holding structure with a lamp located 20 at the focal point of the lens combination;

Fig. 2 is a fragmentary rear view of Figure 1;

Fig. 3 is a plan view, showing a part 25 in section of a light bending device;

Fig. 4 is a rear end elevation of said device; and

Fig. 5 is an elevation of the beam image receiving surface.

In all of the views the same reference 30 characters indicate similar parts.

When it becomes desirable to reflect light rays or beams from a reflector or to project them through a lens or lens-combination from a source of light, intense in effect, but 35 of small contracted dimensions, such as an incandescent lamp with a contracted filament it is very essential for securing the highest efficiency, that the light source be accurately located at the focal point of the 40 reflector or lens.

The most effective known method of accomplishing this result is to adjust the light source or lamp in relation to the lens, and measure the intensity of light beam with a 45 photometer after it passes through the lens and after each adjustment is made until the most effective position of the lamp has thus been empirically found.

By this method or mode of procedure, the 50 lamp or source of light can be located at the focal point of the lens or reflector to yield maximum beam candle power for producing parallel beams, or alternatively diverging beams of any desired spread. This

method of procedure will produce accurate 55 results but it is not available outside of the laboratory.

When the lens-combination is used in signal lights as shown on the drawings, such as railway signals, in which situations 60 they are usually mounted on poles they are, therefore, not accessible for the described photometric determination.

If electric lamps used in such signal devices were indestructible there would be no 65 demand for my lamp focusing invention, because there would be no requirement for replacement of lamps while the signalling device was in service. Unfortunately, lamps used for the purpose are short lived 70 and the installation of a new lamp in precisely the required position becomes immediately necessary and while the signal device is in service position. Owing to tolerance in commercial production of lamps 75 the filament of lamps of the same type and general character vary in position with respect to their attaching means and when placed in the signal device the filament may be considerably displaced from the focusing 80 point of the lens.

One of the objects of the invention is to provide an improved method and means whereby a new lamp, or a replacement can be accurately located at a focal point of a 85 lens or reflector while the apparatus is in service position and while the operative is in a precarious position on the signal supporting post or pole.

As shown on the drawings: 90

The structure is composed of the lens 10 and the lens 12 and the color roundel 13. The focal point of this combination is at F.

A ray of light, such as 14, striking the lens 10 near its perimeter will be reflected to the angle 15 and when passing thru lens 12 near its perimeter, it will be reflected to the angle 16 and drawn out parallel to the common axis of the lens combination. The angles 15 and 16 will bear a definite relation to each other when the light source is located at F. If the light source be shifted back and forth, the angles 15 and 16 will be changed. Shifting of the focal point F will also cause a change in angle 17. 100 Angles 17, 15 and 16 bear a definite relation to each other and to the lenses.

From this fact it is obvious that any

change in position of the source of light from the focal point F will cause a change in the values of these three angles. The operation and results obtained by the device 5 is based upon the foregoing facts.

The focus finding attachment is situated in relation to the lens as to give an indication of any change in the angle of the light rays passing thru lens 10. After passing 10 thru lens 10, light ray 18 is intercepted by the reflector 19 and turned or bent backward as shown at 20. This intercepted ray is caused to impact or strike the transparent or translucent plate or disk 21, such as a 15 ground glass plate which is held in definite position with respect to the lens mounting. When viewed from the rear of the lens mounting the reverted ray of light will appear as a bright spot. When the lamp is at 20 the true focal point of the lens, the spot of light will appear at the center of the disk 21 near the indicated region 22. If the angle ray 18 be changed the position of the spot of light will not appear in the center 25 of the disk. By shifting the light source, the spot of light can be made to appear at 22, the center of the disk 21, at which time the lamp will then be located at the true focal point of the lens.

30 The means for segregating and reflecting the beam or ray of light 18, as described, is a removable and replacable housing, consisting of a tubular part 24 and 25. At the inner junction of these tubes the reflector or 35 mirror 19 is mounted with its reflecting face at a definite angle with respect to the tube 25. The tube 25 has a passage 29 therein thru which the ray 18 is adapted to project. The refracted ray 18 passes thru tube 25, 40 strikes the reflector 19 and is reflected thru tube 24, and impinges on disk 21 as heretofore described.

The tube 24 has a projecting arm 28 integrally formed thereon which carries a lug 45 30, which enters a hole made in the frame 31 for accurate mounting of the reflector housing.

The frame 31 serves as a support for the lenses 10—12 and the roundel 13.

50 The ring support 31 is held in another ring support 33 which comprises the lamp housing.

A lamp 35 is removably supported in a 55 socket 36 and the latter is mounted on a vertical stem 37. The stem 37 is vertically adjustable in the clamp 38. The clamp 38 is a part of a horizontal stem 39. The stem 39 is held in a clamp 40 which is a part of the frame 31 and said stem 39 is movable 60 longitudinally in the clamp.

It is obvious that the lamp 35 may be adjusted and held in any position within the

region of the focusing point of the lens by the arrangement just described.

I am aware that many changes may be 65 made and numerous details of construction may be varied through a wide range without departing from the principles of this invention and I therefore do not purpose limiting the patent granted hereon, other- 70 wise than necessitated by the prior art.

What I claim is:

1. The method of locating a source of light at the focal point of an optical system which includes establishing a light at the 75 focal point by photometric measurements; segregating a ray of light from the focused light near the perimeter thereof and indicating its position; substituting another source of light and adjusting its position 80 in line with said indication to locate said light at said focal point.

2. A focus finding attachment comprising a fixed body; a circular light-receiving and light-projecting body; a source of light near the focal point of the latter body; means for segregating a ray of light near the perimeter of said body and emanating from the focal point of said projector and means for adjusting said light with respect to the afore- 90 said focal point until the segregated ray therefrom is directed into a predetermined path.

3. A focus finding attachment comprising a fixed body; a lens supported on said 95 body; a lamp supported on said body and adjustable in position with respect to the focal point of said lens; means to intercept a ray of light, after it has passed thru said lens near the perimeter thereof, and bending 100 it rearwardly; a surface to receive said bent ray of light, having an indicating mark thereon and means to adjust the position of said lamp to vary the position of said bent ray with respect to said mark on said receiving surface.

4. A focus finding attachment comprising a fixed body; a lens supported on said body; a lamp movably supported on said body, adjustable in position with respect to the focal point of said lens; means supported on said body and removable therefrom to intercept a ray of light after it has passed thru said lens near the perimeter thereof; means to accurately position the replaced 110 intercepting means on said body; a light-receiving surface for said intercepted ray of light; an indicating mark on said surface and means to adjust the position of the lamp with respect to said mark.

In testimony whereof I have hereunto subscribed my name.

DANIEL J. McCARTHY.
